BUTTON MANUFACTURING COMPANY, OF PORTSMOUTH, NEW HAMPSHIRE, A
CORPORATION OF MAINE.

SEVERING MECHANISM FOR WET-PAPER MACHINES.

Application filed October 19, 1923. Serial No. 669,460.

To all whom it may concern:

Be it known that I, EDWARD C. BATCHELDER, a citizen of the United States, residing at Portsmouth, in the county of Rockingham and State of New Hampshire, have invented new and useful Improvements in Severing Mechanism for Wet-Paper Machines, of which the following is a specification.

- 10 This invention relates to a severing device for wet paper machines.
The object of the invention is to provide an automatic severing device and mechanism whereby when the paper on the make-up roll of a wet paper machine shall have arrived at a certain thickness, the said mechanism will be automatically operated to sever the paper on the make-up roll entirely there-across, the paper thus severed being then imme-
20 diately removed from the make-up roll by the operator and the automatic mechanism returning to its first position, in order to repeat the severing operation.

The invention contemplates an adjustable feature whereby the severing mechanism may be operated when the paper arrives at any predetermined thickness upon the make-up roll.

The mechanism of this invention is further provided with safety means whereby if any unforeseen condition should arise in the operation of the mechanism, whereby undue strain may be brought to bear upon any of the parts thereof, the safety means will operate to prevent breakage or injury to any of the parts of the mechanism.

The wet paper machine to which this invention is particularly adapted is well known to those skilled in the art and embodies therein a make-up roll, a guide roll and a belt which passes between the make-up roll and the guide roll and thus conveys the paper pulp to the make-up roll and deposits it thereon, all in a manner well-known to those skilled in this art.

The invention consists in the automatic severing mechanism hereinafter set forth in the specification and particularly pointed out in the claims and in the combination of the same with a wet paper machine.

Referring to the drawings:—

Figure 1 is a front elevation partly broken away illustrating the automatic severing mechanism of my invention as embodied in

a wet paper machine, only a portion of the 55 wet paper machine being shown, namely, the make-up roll, a portion of the guide roll and a portion of the paper feeding belt.

Fig. 2 is a sectional elevation taken on line 2—2, Figure 1 and viewed in the direction of the arrows thereon.

Fig. 3 is a side elevation taken from the right of Figure 1.

Fig. 4 is an enlarged front elevation of a portion of the clutch shifting mechanism. 65

Fig. 5 is a front elevation similar to Fig. 4, illustrating the parts in different positions.

Figs. 6, 7 and 8 illustrate enlarged details of a portion of the clutch shifting mechanism in different operative positions. 70

Fig. 8^a is a detail sectional elevation taken on line 8^a—8^a, Fig. 5.

Figs. 9, 10 and 11 are sectional plans in enlarged detail taken on line 9—9, Figure 1, illustrating the two clutch members and the 75 contact members mounted thereon, whereby one of the clutch members is moved away from the other after the severing operation has been performed.

Like numerals refer to like parts throughout the several views of the drawings.

In the drawings, 10 is the frame of the machine comprising two side standards 11 and 12 in which is slidably mounted a frame 13 comprising two slides 14 and 15 slidably mounted respectively in the standards 11 and 12 and rigidly fastened together by a cross beam 16. 17 is the make-up roll of a wet paper machine, which is fastened to a shaft 18 rotatably mounted in bearings in 90 the slides 14 and 15 of the slide frame 13. 19 is a cutter shaft also rotatably mounted at its opposite ends in the slides 14 and 15 forming a part of the slide frame 13. The cutter shaft 19 has a flange 20 extending 95 longitudinally on one side thereof, to which a cutter blade 21 is fastened and diagonally opposite said flange and cutter blade the cutter shaft 19 is provided with a plurality of counter-weights 22 integral therewith. 100

A gear 23 is rotatably mounted upon the cutter shaft 19 and meshes into a gear 24 fast to the make-up roll shaft 18. The make-up roll 17 is rotated by the paper pulp carrying belt 25 which passes from the wet paper machine over a roll 26 and downwardly therefrom beneath the make-up roll 17 and on to a guide roll 27, the paper pulp

28 on the belt thus being transferred to the make-up roll 17. Rotary motion is imparted to the make-up roll by the belt 25 and thus the gears 23 and 24 will be rotated 5 in the direction indicated by the arrows thereon. The gear 23 has a hub 29 thereon provided with a recess 30 in its outer edge and said gear and hub constitute one member of a clutch 31. The other member 32 of 10 the clutch is splined to the cutter shaft 19 and is slideable longitudinally thereon. The member 32 has a projection or a tooth 33 thereon adapted to engage the recess 30 in the hub 29 when moved longitudinally of 15 the shaft 19, or toward the left Figure 1. The clutch member 32 is moved longitudinally of the shaft to cause the same to engage the clutch member 29 by a shifting lever 34 which is pivoted at 35 to a bracket 36 forming 20 a part of the slide 15.

The lever 34 is bifurcated at its lower end and embodies at said lower end two arms 37 and 38 to which is pivotally mounted, by trunnions 39 and 40, a two-part segmental ring 41 which has a groove 42 engaged by a flange 42' on the periphery of the clutch member 32. It will thus be seen that if the upper end of the lever 34 is rocked toward the right Figure 1, the clutch 25 member 32 will be thrown into engagement with the clutch member 29 and vice versa. The shifting lever 34 is moved at its upper end toward the right, Figure 1, to throw the member 32 into engagement with the member 29 by mechanism actuated by the movement of the make-up roll 17 upwardly, which is caused by the paper pulp 28 being deposited thereon by the belt 25. This mechanism will now be described.

40 When the make-up roll is moved upwardly as hereinbefore described, the frame 13 will also move upwardly and a hardened plate 43 will engage a screw 44 which has screw-threaded engagement with a lever 45 pivoted at 46 to the lower end of a vertical rod 47 which is slideably mounted in a bracket 48. A lever 49 is pivoted at 50 to a link 51, which in turn is pivoted at 52 to a bracket 53 fastened to a cross beam 54 which forms a part of the frame of the machine and is rigidly fastened at its opposite ends to the side frames 11 and 12. The lever 49 is connected by a pin 55 to the rod 47 and has a counter-weight 56 fastened to its outer end. It will be seen that any undue resistance to the upward movement of the lever 45, when the same is engaged by the plate 43, forming a part of the slide frame 13, will cause the pivot 46 and rod 47 to be moved upwardly tipping the lever 49 upon its pivot 50.

The end of the lever 45, opposite that to the pivot 46, has depending therefrom an arm 57 which is connected to said lever by a pin 58, and at the lower end of the arm

57 a spring-actuated latch 59 is slidably mounted. The outer end of said latch normally projects beneath a projection 60 rigidly fastened to a spring-actuated stop 61, which is slidably mounted in an auxiliary 70 frame 62 which is fastened to the cross beam 54 of the frame of the machine. The lower end of the spring-actuated stop 61 normally projects into a notch 63 in a spring-actuated member 64. The spring-actuated member 75 64 is connected by a link 65 to the upper end of the shifting lever 34 by a pin 66. The spring-actuated member 64 is slidably mounted in the auxiliary frame 62 and projects into a casing 67, which is provided 80 with a chamber 68 containing a spring 69. One end of the spring 69 bears against a collar 70 having screw-threaded engagement, with the spring-actuated member 64. The other end of said spring bears against one 85 end of the chamber 68.

The casing 67 is pivotally connected at 71 to the vertical arm of the bell-crank lever 72, pivoted at 73 to the auxiliary frame 62. The horizontal arm 74 of said bell-crank lever is pivotally connected at 75 to the latch carrying arm 57. A bell-crank lever 76 is pivoted at 77 to the auxiliary frame 62 and the outer end of the horizontal arm 76' is provided with an inclined surface 78 which is engaged, when the parts are in the relative positions illustrated in Fig. 5, by a rectangular projection 79 fast to the member 64. The vertical arm of the bell-crank lever 76 has a rocker plate 80 pivoted there-to at 81. This rocker plate normally bears against a shoulder 82 on the bell-crank lever 76.

The clutch member 32 is thrown out of engagement with the clutch member 29 by 105 a pair of contact members 83 and 84 which are pivoted at 85 and 86 respectively to the clutch member 29 and to the lower end of the shifting lever 34. Normally these contact members are in the relative positions illustrated in Fig. 9 and are held in such positions by springs 87 and 88 respectively. The contact member 83 has a segmental arm 89 thereon and a stop arm 90. The contact member 84 has a segmental arm 110 91 and a stop arm 92. The curved contact face 89' of the contact member 83 is eccentric to its pivot 85 and the curved contact face 91' of the contact member 84 is eccentric to its pivot 86.

When the parts are in the positions illustrated in Fig. 9, the spring 87 holds one end 93 of the segmental arm 89 against the face 94 of a plate 95, which is fastened by screws 96 to the clutch member 29 and forms a part thereof. At the same time the end 97 of the segmental arm 91 abuts against a stop face 98 on the lower end of the lever 34 and is held thereagainst by the spring 88.

When the contacts 83 and 84 are in the 130

relative positions illustrated in Fig. 11 then further rotation of the gear 23 of the clutch the stop arm 90 abuts against the face of the member 29 will cause the cutter shaft 19 to plate 95 and the stop arm 92 abuts against be rotated in the direction of the arrow *c*, the stop face 99, as illustrated in Fig. 11. Figs. 1 and 2, and the cutter plate 21 will

5 The general operation of the mechanism hereinbefore specifically described is as follows: Assuming the parts to be in the relative positions illustrated in the drawings, Figs. 1, 2, 3, 4, 6 and 9: As the paper pulp 10 board mounts up on the make-up roll 17, the said make-up roll will be moved away from the guide roll 27 and will carry with it, through its shaft 18, the slide frame 13 and will therefore move upwardly at the same time. the gear 24, cutter shaft 19 and its cutter blade 21, the gear 23 and clutch member 29, of which it forms a part, the clutch member 32 and the shifting lever 34, link 65, 15 rocking on the pivots at its opposite ends to enable this movement to take place. At this time the clutch member 32 is out of engagement with the clutch member 29 and the contact members 83 and 84 are out of contact with each other, so that as the gear 23 of the 20 clutch member 29 is rotated, it being rotatably mounted upon the shaft 19, the contact member 83 will pass the contact member 84, but will not contact therewith.

Upon continued upward movement of the make-up roll 17, the cross beam 16 will move its plate 43 into contact with the lower end 30 of the adjusting screw 44. This will move the lever 45 upwardly at the right hand end thereof, Fig. 1, thus lifting the latch arm 57 and latch 59, and as the latch at that time projects beneath the plate 60, forming a part 35 of the spring-actuated stop 61, said stop 61 will be raised and the lower end of the same 40 spring-actuated member 64, which will then move forward from the position occupied in Fig. 6 to the position occupied in Fig. 7. At the same time the bell-crank lever 76 will 45 and the rocker plate 80 will have become disengaged from the upper edge of the latch 59. The spring-actuated member 64 will thus 50 move in the direction of the arrow *a*, Fig. 6, and through the connecting link 65 will 55 cause the shifting lever 34, at its upper end, to move toward the right, Fig. 1, the lower end moving in the opposite direction and carrying with it the clutch member 32, 60 whereupon the projection 33 on said clutch member 32 will enter the depression 30 in the clutch member 29 and these two clutch 65 members will then be in operative engage-

ment. The further rotation of the gear 23 of the clutch member 29 will cause the cutter shaft 19 to be rotated in the direction of the arrow *c*, Figs. 1 and 2, and the cutter plate 21 will engage the layer of paper 28 on the make-up 70 roll 17 and will sever the same.

The operator then takes hold of the severed paper board on the make-up roll, on the upper part of the roll, and draws it towards him as the roll 17 continues to rotate and this will feed the severed paper board out of the machine. The cutter shaft 19 will rotate with its cutter 21 to its original position illustrated in Fig. 2 and then will stop, due to the fact that the clutch is thrown out of operation by the member 32 being thrown toward the right, Figs. 1 and 11, and this is caused by the contact member 83 on the clutch member 29 engaging the contact member 84 on the lower end of the shifting 85 lever 34 as illustrated in Fig. 10.

Further rotation of the clutch member 29 will cause the contact members to assume the relative positions illustrated in Fig. 11 and will move the lower end of the shifting 90 lever, upon which the contact member 84 is pivotally mounted, toward the right, from the position illustrated in Fig. 10 to the po-

sition illustrated in Fig. 11. During this movement the contact members 83 and 84 95

will rock upon their pivots from the positions illustrated in Fig. 10 to that illustrated in Fig. 11 with the stop arms 90 and 92 in contact with their respective stop surfaces, and as the contact surfaces 89 and 91 are 100 eccentric to their respective pivots, the lower end of the shifting lever 34 will be moved

will be raised and the lower end of the same to a sufficient distance toward the right, or will be disengaged from the notch 63 in the outwardly from the clutch member 29, so

that when the contact member 83 has been 105 moved slightly beyond the position shown in Fig. 11 in its circular path, the two contact members will, by the action of their

rock into the position illustrated in Fig. 7 respective springs 87 and 88, be returned to the positions illustrated in Fig. 9, where-

upon the contact member 84 will be moved 110 to a substantial distance out of the path of the contact member 83, so that in the opera-

tion of the machine, and the further rotation of the clutch member 29, the contact 115 members 83 and 84 will not contact until the foregoing operation is repeated.

When the shifting lever is rocked by the contact members, as just described, the up-

per end thereof will be moved toward the left, Figs. 1 and 5, and this will move the

members 83 and 84 toward the left, and its collar 70 in the casing 67 will also

be moved toward the left, from the position illustrated in Fig. 5 to that illustrated in

Fig. 4 and thus will compress the spring 69, which during the operation hereinbefore de-

will bring the contact member 84 into the scribed, expanded while moving the member 64 toward the right. Furthermore, during

60 At the same time the contact member 84 on the lower end of the shifting lever 34 will be brought toward the left, moving in the direction of the arrow *b*, Fig. 10, and this will bring the contact member 84 into the rotary path of the contact member 83. The clutch members now being locked together 65

the movement of the member 64 toward the

left, the projection 79 acting against the inclined face 78 on the bell-crank lever 76 will rock said lever toward the left, Fig. 7 and will bring the left hand edge of the rocker plate 80 into contact with the end of the latch 59 and will push said latch toward the left compressing its spring 59', Fig. 4, and the parts will then assume the relative positions illustrated in Fig. 8, with the end of the latch resting against the left face of the rocker plate and with the lower edge of the horizontal arm of the bell-crank lever 76 riding against the top of the projection 79.

When the latch 59 is moved from the position illustrated in Fig. 7 to that illustrated in Fig. 8, it will be pushed out from under the plate 60 forming a part of the spring-actuated stop 61 and this will release the stop 61, which will then be forced downwardly by its spring 61', Fig. 4, and assume its original position as illustrated in Fig. 4, with the lower end of the stop 61 projecting into the notch 63 on the spring-actuated member 64, and thus locking said spring-actuated member against movement toward the right, Fig. 6, and consequently the shifting lever 34 and the clutch member 32 and the contact member 84 will be locked in the respective positions illustrated in Figs. 1, 4, 6 and 9.

When the paper board has been removed from the make-up roll by the operator, as hereinbefore described, the make-up roll 17 will move downwardly to contact with the belt 25 and this will carry the slide frame 13 downwardly together with the cutter shaft and cutter and other parts mounted thereon, whereupon the latch 59 will be lowered from the position illustrated in Fig. 8 to the position illustrated in Fig. 6 and will be forced by its spring 59' toward the right and beneath the rocker plate 80 and the projection 60 on the stop rod 61 and the parts are then in the relative positions illustrated in Figure 1 ready to again perform the operation hereinbefore described and sever another section of paper board upon the make-up roll 17.

If any obstruction, or if for any cause, undue opposition to the movement upwardly of the lever 45 at the right hand end thereof, should arise, the lever 45 would then be moved upwardly at its left hand end by the slide frame 13 and this it would be enabled to do by reason of the rod 47 sliding upwardly in the bracket 48 and rocking the lever 49 on its pivot 50. When the obstruction, or other cause, has been removed, then the weight 56 will force the rod 47 downwardly and the parts will assume the relative positions illustrated in Figure 1.

The construction last described prevents breakage or injury to the different parts of the mechanism when any undue strain is brought to bear thereon for any reason.

It will be seen that by adjusting the screw 44 downwardly, the mechanism hereinbefore described will be operated sooner than when the screw 44 is adjusted upwardly and therefore, the slide 13 would have to travel a less distance before the cutter is operated to sever the paper board in one instance, than in the other, thus the thickness of the paper board which is removed from the make-up roll may be predetermined by adjusting the screw 44.

The clutch mechanism per se, while having been fully described and illustrated in the foregoing specification and in the drawings, in order to disclose one form of clutch, whereby the severing of the paper board may be accomplished, is made the subject matter of a separate application filed by me of even date herewith, Serial No. 669,459.

I claim:

1. A wet paper machine having, in combination, a make-up roll, a paper feed belt, a guide roll for said belt coacting with said make-up roll, a rotatable cutter adapted to coact with said make-up roll, a slide frame upon which said make-up roll and rotary cutter are rotatably mounted and mechanism actuated by the movement of said slide frame away from said guide roll for automatically operating said cutter to sever the paper on said make-up roll.

2. A wet paper machine having, in combination, a make-up roll, a shaft therefor, a paper feed belt, a guide roll for said belt coacting with said make-up roll, a cutter, a rotary shaft upon which said cutter is mounted, a frame in which said shafts are journaled, a clutch mounted on said cutter shaft and mechanism operated by the movement of said frame away from said guide roll to throw said clutch into operation, whereby said cutter may be rotated to sever the paper on said make-up roll.

3. A wet paper machine having, in combination, a make-up roll, a shaft therefor, a paper feed belt, a guide roll for said belt coacting with said make-up roll, a cutter, a rotary shaft upon which said cutter is mounted, a slide frame in which said shafts are journaled, a clutch mounted on said cutter shaft, one member of said clutch embodying a gear, a gear on said make-up roll meshing into said clutch gear and mechanism operated by said slide frame adapted to throw another member of said clutch into engagement with said first-named member, whereby said cutter shaft may be rotated and said cutter operated to sever the paper on said make-up roll.

4. A wet paper machine having, in combination, a make-up roll, a movable frame upon which said make-up roll is rotatably mounted, a paper feed belt, a guide roll for said feed belt coacting with said make-up roll, a cutter rotatably mounted on said mov-

able frame adapted to coact with said make-up roll, a clutch for imparting a rotary motion to said cutter and mechanism actuated by the movement of said make-up roll 5 and its frame away from said guide roll to throw said clutch into operation whereby said cutter may be operated to sever the paper on said make-up roll.

5. A wet paper machine having, in combination, a make-up roll, a movable frame upon which said make-up roll is rotatably mounted, a paper feed belt, a guide roll for said feed belt coacting with said make-up roll, a cutter rotatably mounted on said movable 15 frame adapted to coact with said make-up roll, a clutch for imparting a rotary motion to said cutter and mechanism actuated by the movement of said make-up roll and its frame away from said guide roll to throw 20 said clutch into operation whereby said cutter may be operated to sever the paper on said make-up roll and means to throw said clutch out of operation after said paper has been severed.

25. 6. A wet paper machine having, in combination, a make-up roll, a movable frame upon which said make-up roll is rotatably mounted, a paper feed belt, a guide roll for said feed belt coacting with said make-up roll, a cutter rotatably mounted on said movable 30 frame adapted to coact with said make-up roll, a clutch for imparting a rotary motion to said cutter, a shifting lever and mechanism actuated by the movement 35 of said make-up roll and its frame away from said guide roll to rock said lever and throw said clutch into operation, whereby said cutter may be operated to sever the paper on said make-up roll.

40. 7. A wet paper machine having, in combination, a make-up roll, a movable frame upon which said make-up roll is rotatably mounted, a paper feed belt, a guide roll for said feed belt coacting with said make-up 45 roll, a cutter rotatably mounted on said movable frame adapted to coact with said make-up roll, a clutch for imparting a rotary motion to said cutter, a shifting lever, mechanism actuated by the movement of said make-up roll and its frame away from said guide roll to rock said lever and throw said clutch into operation, whereby said cutter may be operated to sever the paper on said make-up roll and means on said 55 clutch to rock said shifting lever and throw said clutch out of operation.

8. A wet paper machine having, in combination, a make-up roll, a movable frame upon which said make-up roll is rotatably mounted, a paper feed belt, a guide roll for said feed belt coacting with said make-up roll, a cutter rotatably mounted on said movable frame adapted to coact with said make-up roll, a clutch for imparting a rotary motion to said cutter, a shifting lever, 60

mechanism actuated by the movement of said make-up roll and its frame away from said guide roll to rock said lever and throw said clutch into operation, whereby said cutter may be operated to sever the paper on said make-up roll, means on said clutch to rock said shifting lever and throw said clutch out of operation and means to lock 70 said lever with said clutch out of operation.

9. A wet paper machine having, in combination, a make-up roll, a movable frame upon which said make-up roll is rotatably mounted, a paper feed belt, a guide roll for said feed belt coacting with said make-up roll, a cutter rotatably mounted on said movable 75 frame adapted to coact with said make-up roll, a clutch for imparting a rotary motion to said cutter, a shifting lever, a spring-actuated member connected to said shifting lever, a stop engaging said spring-actuated member and mechanism actuated by the movement of said make-up roll away from said guide roll to move said stop and release said spring-actuated member to rock 80 said lever in one direction and throw said clutch into operation whereby said cutter may be operated to sever the paper on said make-up roll.

10. A wet paper machine having, in combination, a make-up roll, a movable frame upon which said make-up roll is rotatably mounted, a paper feed belt, a guide roll for said feed belt, coacting with said make-up roll, a cutter rotatably mounted on said movable 85 frame adapted to coact with said make-up roll, a clutch for imparting a rotary motion to said cutter, a shifting lever, a spring-actuated member connected to said shifting lever, a stop engaging said spring-actuated member, mechanism actuated by the movement of said make-up roll away from said guide roll to move said stop and release said spring-actuated member to rock said lever in one direction and throw said clutch into operation, whereby said cutter may be operated to sever the paper on said make-up roll.

11. A wet paper machine having, in combination, a make-up roll, a movable frame upon which said make-up roll is rotatably mounted, a paper feed belt, a guide roll for said feed belt coacting with said make-up roll, a cutter rotatably mounted on said movable 100 frame adapted to coact with said make-up roll, a clutch for imparting a rotary motion to said cutter, a shifting lever, a spring-actuated member connected to said shifting lever, a stop engaging said spring-actuated member, mechanism actuated by the movement of said make-up roll away from said guide roll to move said stop and release said spring-actuated member to rock said lever in one direction and throw said clutch into operation, whereby said cutter may be operated to sever the paper on said make-up roll and means on said clutch to rock said lever in the opposite direction to throw said clutch out of operation.

12. A wet paper machine having, in combination, a make-up roll, a movable frame upon which said make-up roll is rotatably mounted, a paper feed belt, a guide roll for said feed belt coacting with said make-up roll, a cutter rotatably mounted on said movable frame adapted to coact with said make-up roll, a clutch for imparting a rotary motion to said cutter, a shifting lever, a spring-actuated member connected to said shifting lever, a stop engaging said spring-actuated member, mechanism actuated by the movement of said make-up roll away from said guide roll to move said stop and release said spring-actuated member to rock said lever in one direction and throw said 115

clutch into operation, whereby said cutter may be operated to sever the paper on said make-up roll, and means on said clutch to rock said lever in the opposite direction 5 to throw said clutch out of operation, and enable said stop to engage said spring-actuated member and lock said shifting lever with said clutch out of operation.

12. A wet paper machine having, in combination, a make-up roll, a paper feed belt, a guide roll for said feed belt coacting with said make-up roll, a rotatable cutter adapted to coact with said make-up roll, a clutch for imparting a rotary motion to said cutter, a shifting lever, a spring-actuated member connected to said shifting lever, a spring-actuated stop engaging said spring-actuated member, a spring-actuated latch engaging said spring-actuated stop, a bell-crank lever, 15 a rocker plate pivoted thereon and adapted to engage said latch and disengage it from said spring-actuated stop, said bell-crank lever being adapted to be actuated by said spring-actuated member alternately in opposite directions, mechanism actuated by the movement of said make-up roll away from said guide roll to lift said latch and spring-actuated stop and disengage said spring-actuated member to allow it to rock said shifting lever in one direction and throw said clutch into operation, whereby said cutter may be operated to sever the paper on said make-up roll and means on said clutch to rock said shifting lever in the opposite direction to throw said clutch out of operation and to move said spring-actuated member and bell-crank lever and cause said rocker plate to release said stop and allow it to lock said spring-actuated member 35 against its respective spring.

13. A wet paper machine having, in combination, a make-up roll, a paper feed belt, a guide roll for said feed belt coacting with said make-up roll, a rotatable cutter adapted to coact with said make-up roll, a clutch for imparting a rotary motion to said cutter, a shifting lever, a spring-actuated member connected to said shifting lever, a spring-actuated stop engaging said spring-actuated member, a spring-actuated latch engaging said spring-actuated stop, a bell-crank lever, 45 a rocker plate pivoted thereon and adapted to engage said latch and disengage it from said spring-actuated stop, said bell-crank lever being adapted to be actuated by said spring-actuated member alternately in opposite directions, and mechanism actuated by the movement of said make-up roll away from said guide roll to lift said latch and spring-actuated stop and disengage said spring-actuated member to allow it to rock 55

said shifting lever in one direction and throw said clutch into operation, whereby said cutter may be operated to sever the paper on said make-up roll, means on said clutch to rock said shifting lever in the opposite direction to throw said clutch out of operation and to move said spring-actuated member and bell-crank lever and cause said rocker plate to release said stop and allow it to lock said spring-actuated member against its respective spring, said mechanism being adapted, upon the movement of said make-up roll toward said guide roll, to bring said latch into engagement 65 with said spring-actuated stop.

14. A wet paper machine having, in combination, a make-up roll, a paper feed belt, a guide roll for said belt coacting with said make-up roll, a rotatable cutter adapted to 70 coact with said make-up roll, a movable frame upon which said make-up roll is rotatably mounted, a lever adapted to be engaged by said frame when it is moved by said make-up roll and mechanism actuated 75 by said lever for automatically operating said cutter to sever the paper on said make-up roll.

15. A wet paper machine having, in combination, a make-up roll, a paper feed belt, a guide roll for said belt coacting with said make-up roll, a rotatable cutter adapted to coact with said make-up roll, a movable frame upon which said make-up roll is rotatably mounted, a lever, a screw having 90 screw-threaded engagement with said lever and adapted to be engaged by said frame when it is moved by said make-up roll and mechanism actuated by said lever for automatically operating said cutter to sever a 95 layer of paper on said make-up roll.

16. A wet paper machine having, in combination, a make-up roll, a paper feed belt, a guide roll for said belt coacting with said make-up roll, a rotatable cutter adapted to 105 coact with said make-up roll, a movable frame upon which said make-up roll is rotatably mounted, a lever adapted to be engaged by said frame when it is moved by said make-up roll, a pivot for said lever 110 adapted to be moved thereby when under abnormal stress and mechanism actuated by said lever for automatically operating said cutter to sever the paper on said make-up roll.

In testimony whereof I have hereunto set my hand in presence of two subscribing witnesses.

EDWARD C. BATCHELDER.
Witnesses:

HENRY B. TILTON,
ELLEN MORRISSEY.
